ASH CAN

Application filed March 2, 1932. Serial No. 596,262.

This invention relates to a receptacle for receiving ashes and other refuse and refers more particularly to the means for hingedly supporting and operating the lid.

5 One of the objects is to provide the receptacle with an external housing for receiving, supporting and partially concealing the lid supporting and operating mechanism.

One of the specific objects is to mount the 10 lid upon a pair of angular brace levers which are pivotally mounted upon the housing to swing about a horizontal axis and to extend the brace levers downwardly from said axis for receiving and supporting a suitable hand 15 bail in such manner that the latter may project below the housing where it is easily accessible for opening and closing the lid and also for manipulating the receptacle to different positions for carrying and dumping.

20 Other objects and uses will be brought out in the following description.

In the drawing:

Figure 1 is a top plan of my improved receptacle, the lid being closed.

25 Figure 2 is a vertical sectional view of the same receptacle taken in the plane of line 2-2, Figure 1.

Figure 3 is a detail vertical sectional view 30 through the housing taken on line 3-3, Figure 2.

In order that the invention may be clearly understood, we have shown an upright cylindrical receptacle 1 having a bottom portion 2 and a lid section 3, the upper 35 end of the receptacle being provided with the usual out-turned bead 1' while the lid 3 is provided with a downturned marginal flange 3' adapted to fit more or less snugly upon the bead 1' to form a substantially airtight seal therewith.

A housing 4 is rigidly and permanently secured to the outer periphery of one side of the receptacle 1 to project outwardly therefrom a distance considerably less than 45 the radius of the receptacle.

This housing 4 is mainly rectangular in that it comprises an outer upright wall 5 and opposite upright side walls 6, which latter are arranged in parallel planes 50 and have their inner edges spot-welded or

otherwise permanently secured to the periphery of the receptacle 1 to form a unitary part thereof, the outer wall 5 being preferably parallel with the axis of the receptacle.

The height of the housing 4 is considerably less than that of the receptacle and is arranged relatively nearer the top than the bottom and is reinforced at its upper and lower ends by bands 4' as shown more clearly in Figure 2.

55 A pair of angular brace levers 7 are pivoted at 8 to the inner faces of the opposite side walls 6 to swing about a horizontal axis, said brace levers being extended upwardly and downwardly from said axis to 60 form upper and lower arms 7' and 7'', the upper arms being extended across and upon the upper face of the lid 3 in parallel spaced relation and are permanently secured to said lid by spot-welding or other 65 well known fastening means to cause the lid to swing therewith.

70 The portions of the arms 7' overlying the lid 3 are connected by tie bars 9 and also by a handle bar 10 which is 75 located at the side of the axis of the receptacle 1 opposite the pivots 8 for a purpose hereinafter described, the tie bars 9 and 10 being spot-welded or otherwise secured to the arms 7 for stiffening 80 the latter.

The lower arms 7'' are arranged to swing between the outer wall 5 of the housing 4 and adjacent side of the receptacle 1 for opening and closing the lid in a manner presently described, said arms being arranged in such manner with relation to the outer and inner walls of the housing that when the lid is open to the position shown by dotted lines in Figure 2, the lower 85 ends of the arm 7'' will engage the adjacent side of the receptacle 1 for limiting the opening movement of the lid in which position the predominance of weight of the lid will be in a plane slightly at the rear of 90 the pivot 8 to automatically hold the lid in its open position.

95 The lower arms 7'' can also be constructed in such a manner with relation to 100 the outer and inner walls of the housing that

when the lid —3— is opened, it will automatically close when released from the open position provided the predominance of the weight of the lid will be in a plane at the front of pivot —8— when the lid has been opened to its maximum.

A handle bail —11— is pivoted at —12— to the lower ends of the arms —7"— to extend downwardly therefrom some distance below the lower end of the housing —4— where it is conveniently accessible to be grabbed by the hand for rocking the brace levers —7— about the axis of the pivot —8— and thereby opening and closing the lid, the handle bail being U-shaped and arranged to move within the housing —4—, as shown more clearly in Figure 2.

The lid —3— is also provided with a handle —10— rigidly secured thereto to be used in conjunction with the handle —11— for lifting, tilting and dumping the receptacle, but obviously either of the handles may be used for opening or closing the lid.

It will be noted that the brace levers —7— are hinged at —8— to the sides of the housing —4— near the upper end thereof and that the lower arms —7"— extend downwardly from the pivot a distance approximately half the length of the housing, the radial depth of the housing and length of the lower arm —7"— being arranged in such manner that the arc of movement of the lower end of the arm —7"— is approximately equal to the radial depth of the housing so that when the lid is closed it will be in close proximity to the outer wall —5— of the housing and when opened it will be in close proximity to the periphery of the receptacle which forms a limiting stop for the opening movement of the lid.

It will also be noted that the lower and upper arms of the brace levers —7— are movable to opposite sides of the vertical plane of the pivots —8— as the lid is opened and closed and, when the lid is closed, the handle bail —11— will be suspended from the lower end of the arms —7"— closely adjacent the inner face of the outer wall —5— of the housing and, therefore, in a plane at the outside of the vertical plane of the pivots —8—.

As previously stated, the bail handle —11— extends downwardly from its hinged pivots —12— some distance below the lower end of the housing so that its intermediate portion will be registered with the lower end of the front wall —5— of the housing which forms a fulcrum against which the bail handle —11— may bear when it is desired to open the lid.

For example, assuming that the lid is in its closed position and that the brace levers —7— and bail handle —11— are in the positions shown by full lines in Figure 2, then by drawing the bail handle outwardly against

the lower edge of the outer wall of the housing —4— as a fulcrum will rock the upper end of said bail handle and lower end of the brace levers —7— inwardly, thereby opening the lid —3— to the position shown by dotted lines in Figure 2 in which position the predominance of weight is slightly to the inside of the vertical plane of the pivot —8— to cause the lid to automatically remain in its open position.

Under these conditions the bail handle —11— would be released from engagement with the lower end of the outer wall of the housing and forced inwardly against the adjacent wall of the receptacle by its own weight, or, if the lid is opened by the handle —10— to the position shown by dotted lines, Figure 2, the bail handle —11— will be forced inwardly against the adjacent wall of the receptacle.

If it is desired to close the lid when the latter is held open under its own weight, it is simply necessary to push down upon the handle —10— or to draw down upon the bail handle —11— thereby rocking the brace levers —7— about their pivots —8— until the predominance of weight of the lid is inside of the vertical plane of said pivot.

Assuming that the lid —3— and its operating levers —7—, together with the bail handle —11— are in the position shown by full lines in Figure 2 and it is desired to dump the receptacle, it is simply necessary to engage the lower end of the bail handle with one hand and the handle —10— on the lid with the other hand and then to draw outwardly upon the lower end of the bail handle against the fulcrum bearing on the lower end of the outer wall of the housing and at the same time to lift on both handles resulting in automatically opening the lid to approximately the angle shown by dotted lines in Figure 2, after which the entire receptacle may be manipulated to any position necessary for discharging its contents.

It will be noted that the brace levers —7— and lid —3—, together with the bail handle —11—, are all carried by the housing —4— and, therefore, this housing with the parts carried thereby may be made up as a unit to be applied to any similar receptacle by simply spot-welding or otherwise rigidly securing the inner edges of the opposite side members —6— of the housing to the periphery of said receptacle.

The construction shown and described is particularly simple, practical and efficient, but obviously may be modified in certain details without departing from the spirit of the invention, it being understood that one of the objects in mounting the bail handle —11— on the brace levers —7— in the manner described is to enable it to be used in connection with the handle —10— lifting and dumping the

receptacle and simultaneously opening the lid.

What we claim is:

1. The combination with a refuse receptacle, of a housing secured to one side of the receptacle to project outwardly therefrom, a pair of angle braces pivoted to opposite sides of the housing to swing about a horizontal axis and extended upwardly and downwardly from said axis, a lid for the receptacle rigidly secured to the upper arms of said braces to move therewith to and from its closed position, and a handle bail hinged to the lower arms of the braces to swing about an axis parallel with the pivotal axis of the braces and extended downwardly within and below the lower end of the housing.

2. The combination with a refuse receptacle, of a housing secured to one side of the receptacle to project outwardly therefrom, a lid-supporting element pivoted to and within the housing to swing about a horizontal axis for opening and closing the lid, and a bail handle hinged to said element below its pivot and extended downwardly below the lower end of the housing, said bail being adapted to fulcrum against the lower end of the outer wall of the housing when its lower end is drawn outwardly for rocking said element about its pivot to open the lid, or when lifting the can.

3. The combination with a refuse receptacle, and a lid for the receptacle, of a housing secured to one side of the receptacle to project outwardly therefrom, a supporting element for the lid hinged to the housing to swing about a horizontal axis for opening and closing the lid and extended downwardly and outwardly from its hinge when the lid is closed, and a handle hinged to the lower end of said element to swing about an axis parallel with the first named axis and extended downwardly below the lower end of the housing, said housing having an abutment against which the intermediate portion of the handle is adapted to fulcrum when swung outwardly for rocking said element to open the lid, or when lifting the can.

In witness whereof we have hereunto set our hands this 5th day of February, 1932.

MARCUS J. FESSLER.
